UNITED STATES PATENT OFFICE.

JACOB J. LINDAUER, OF NEW YORK, N. Y.

DETACHABLE BUTTON OR STUD.

SPECIFICATION forming part of Letters Patent No. 310,293, dated January 6, 1885.

Application filed October 7, 1884. (No model.)

To all whom it may concern:

Be it known that I, JACOB J. LINDAUER, of the city, county, and State of New York, have invented a new and useful Improvement 5 in Detachable Buttons and Studs, of which the following is a full, clear, and exact description.

Reference is to be had to the accompanying drawings, forming a part of this specification, 10 in which similar letters of reference indicate corresponding parts in all the figures.

Figure 1 is a rear view of one of my improved buttons. Fig. 2 is a side elevation of the same, shown partly closed. Fig. 3 is a 15 side elevation of the same, shown in position as secured in a button-hole, and part being broken away.

The object of this invention is to promote convenience in the use of detachable buttons 20 and studs.

The invention relates to a detachable button or stud constructed with a back plate provided with a spring, and slotted to receive the bent parts of two J-shaped bars, which have 25 teeth in their adjacent convex surfaces, whereby both the said bars will be turned by the movement of either, as will be hereinafter described and claimed.

A represents the rim of a button or stud, 30 which is formed upon or securely connected with the back plate, B, and to which is secured the stone or face-plate C when used.

In the back plate, B, are formed three slots to receive the curved parts of the J-shaped bars D, which form the shank and foot of the button, the parts E of the back plate between the said slots serving as pivots for the bent 35 parts of the bars D to turn upon, the said bars being held in position, when adjusted, by 40 a spring, F, secured to the back plate, B. Upon the adjacent outer or convex surfaces of the curved parts of the bars D are formed

teeth G, which mesh into each other, as shown in Figs. 2 and 3, so that either of the said bars will be turned by the movement of the other 45 bar.

In applying the button or stud the long arms of the J-shaped bars D are brought together and are passed through the button-hole. Then, by pressing the end of either of 50 the short arms of the bars D outward, both the said bars will be turned to bring their long arms into a position parallel with the back plate, B.

In detaching the button the long arm of 55 either of the bars D is pushed inward, which brings both the said bars into the position shown in Fig. 2, so that they can be readily withdrawn from the button-hole.

Having thus described my invention, I claim 60 as new and desire to secure by Letters Patent—

1. In a detachable button or stud, the combination, with the slotted back plate, B, and the spring F, of the J-shaped bars D, having teeth G in their adjacent convex surfaces, 65 substantially as herein shown and described, whereby both the said bars will be turned by the movement of either, as set forth.

2. A detachable button or stud provided with the J-shaped bars D, made substantially 70 as herein shown and described, with teeth G upon their convex surfaces, as set forth.

3. In a detachable button or stud, the combination, with the back plate thereof, of curved locking-bars toothed upon their convex surfaces, and held to be partially revolved in contact with each other upon said back plate, substantially as herein shown and described. 75

JACOB J. LINDAUER.
